UNITED STATES PATENT OFFICE.

GEORGE W. HOWES, OF DOWAGIAC, MICHIGAN, ASSIGNOR TO THE BECKWITH COMPANY, OF DOWAGIAC, MICHIGAN.

GAS STOVE.

Application filed July 19, 1923. Serial No. 652,503.

To all whom it may concern:

Be it known that I, GEORGE W. HOWES, a citizen of the United States, residing at Dowagiac, county of Cass, State of Michigan, have invented certain new and useful improvements in Gas Stoves, of which the following is a specification.

This invention relates to improvements in gas stoves.

10 The main object of this invention is to provide an improved gas stove which is especially adapted for use in burning of natural gas and which provides for the escape of the products of combustion from the open 15 top section and also the oven section with which the stove is provided.

Further objects, and objects pertaining to details are economies of construction and operation of my improvements will definitely 20 appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing forming a part of this application, in which:

30 Fig. I is a front perspective view of a gas stove embodying the features of my invention, the discharge flue for the open top section being indicated by dotted lines.

Fig. II is a detail vertical section on a 35 line corresponding to line 2-2 of Fig. I.

Fig. III is a detail vertical section on a line corresponding to line 3-3 of Fig. I.

Fig. IV is a detail vertical section on a line corresponding to line 4-4 of Fig. III.

40 In the drawing the sectional views are taken looking in the direction of the little arrows at the ends of the section lines and similar numerals of reference indicate similar parts in all of the views.

45 Referring to the drawing, the main frame 1 of the stove is designed to support the oven designated generally by the numeral 2 and the open top section designated generally by the numeral 3. The oven comprises 50 spaced outer and inner top walls 4 and 5 respectively, outer and inner spaced bottom walls 6 and 7 respectively, spaced outer and inner rear walls 8 and 9 respectively, and

also correspondingly spaced outer and inner side walls 10 and 11. 55

The space between the walls 6 and 7 provides a burner chamber 12 for the burner 13. The spaces between the top, side and rear walls provide side, top and rear circulating flues 14, 15 and 16, respectively, communicating with the burner chamber so that the products of combustion pass around the oven. These flues are provided with a flue discharge 17 at the rear of the top, the discharge pipe or flue being omitted. 60 65

The open top section 3 has a closed burner chamber 18 for the burners shown conventionally at 19. The top of this section is provided with lids 20. A discharge flue 21 opens into this burner chamber 18 at 22, the flue being disposed in the rear circulating 70 75 passage 16 and its upper end being preferably disposed below the flue opening 17.

With the parts thus arranged I provide the burner chamber 18 with an effective discharge connection which does not in any way interfere with the flue connections for the oven. The structure is neat and attractive in appearance. 75

My improved gas stove is especially designed by me for the burning of natural gas, although it will be understood that it is desirable for use in other relations where flue connections for all the burners are desired. 80

Having thus described my invention what I claim as new and desire to secure by Letters Patent is:

1. The combination in a gas stove, of an oven comprising spaced inner and outer top, bottom, rear and side walls providing a burner chamber below the oven and communicating rear, top and side circulating passages, there being a flue discharge at the rear of the outer top wall, a second burner chamber disposed at the side of said oven and provided with a grid top, and a discharge flue for said second burner chamber disposed between the said spaced rear walls and extending upwardly therein with its upper end adjacent the said flue discharge of said oven. 90 95 100

2. The combination in a gas stove, of an oven comprising spaced inner and outer top, rear and side walls providing a burner chamber below the oven and communicating rear, top and side circulating passages and 105

having a flue discharge, a second burner chamber disposed at the side of said oven and provided with a grid top, and a discharge flue for said second burner chamber disposed between the said spaced rear walls.

3. The combination in a gas stove, of an oven comprising spaced inner and outer walls providing a circulating passage, there

being a flue discharge for said passage, a burner chamber disposed at the side of said oven and provided with a grid top, and a discharge flue for said second burner chamber disposed in said circulating passage.

In witness whereof, I have hereunto set my hand.

GEORGE W. HOWES. [L.S.]
